UNITED STATES PATENT OFFICE.

ALFRED FALLOT, OF PLAUE, GERMANY; HARRY PRIESTER EXECUTOR OF SAID
ALFRED FALLOT, DECEASED.

SHEET-DELIVERING DEVICE FOR PRINTING PRESSES.

Application filed February 29, 1924, Serial No. 696,001, and in Germany March 7, 1923.

This invention relates to a sheet delivering device for sheet printing presses. In the machines of known type the sheet is taken from the printing cylinder by grippers arranged on an endless chain and conveyed to the delivering pile. The grippers open as soon as the sheet is above the delivering pile so that the sheet drops on the pile, the sheet possessing a speed in the direction in which the gripper is moving. This speed is comparatively great as the speed of the gripper depends on the revolving speed of the cylinder. The sheets are therefore not delivered uniformly and they strike against the stops with a certain shock so that, especially in thin sheets, the edge of the sheet is frequently damaged. According to the invention the sheet is delivered not in the direction in which the gripper chain moves, but in the opposite direction. With this object in view the sheet is gripped by the mechanical grippers, sucking cups or the like at the rear end, the grippers being mounted on a carriage which up to the moment at which the gripper release moves at the same speed or at a lower speed than the sheet in the direction of movement of the gripper whereupon the direction of movement of the slide is reversed and the sheet is delivered on the pile by the slide grippers. A blow pipe is preferably arranged above the sheet to blow upon the front part of the sheet previous to the opening of the chain grippers, said blow pipe oscillating after the chain gripper has opened, so that the air current acts then upon the rear end of the sheet. With the improved device it is possible to regulate the speed of the delivering movement at will; and it will be generally considerably slower than with the known devices. The front edge of the sheet comes first, in contact with the pile, then the middle of the sheet and finally the rear edge of the same, so that a steady and uniform delivering of the sheets is ensured.

The invention will be best understood from a consideration of the following detailed description taken in connection with the accompanying drawings forming a part of this specification, with the understanding that while on the drawings two embodiments of the invention are shown, the invention is not confined to any strict conformity with the showing of the drawings, but may be em-

bodied in any manner which does not constitute a material departure from the salient features of the invention.

In the drawing:

Fig. 1 is a side elevation of the sheet delivering device.

Fig. 2 shows a slightly modified form of construction.

Fig. 3 shows a generic constructive detail in cross section.

The sheet *a* is taken from the printing cylinder *b* by the gripper *c* arranged on the conveyer chain *d* and conveyed to the delivering pile *e*. The sheet *a* passes between the lateral feeding rollers *f* which maintain it stretched so that the sheet is conveyed to the pile in a uniformly stretched position. Below the sprocket wheel *g* which is nearest to the printing cylinder *b* a carriage *h* is arranged which carries a suction pipe *k* with a gripper formed by sucker cups *i*. When the rear end of the sheet *a* has come out from between the feeding rollers *f* the sheet comes in contact with the sucker cups *i* which are put into communication with a partial vacuum and the carriage *h* moves in the direction of the sheet *a* under the influence of the reciprocating toothed segment *l* which is controlled by an eccentric *m*. As soon as the chain gripper *c* has travelled beyond the end of the delivering pile *e* a roller lever *n* connected with the gripper strikes against a curved guide bar *o* whereby the gripper is opened and releases the sheet *a*. At the same time the suction pipe *k* is made to communicate with a space in which vacuum exists so that the rear end of the sheet *a* is sucked upon the sucker cups *i*. The direction of movement of the carriage *h* is reversed and the sheet is brought back upon the delivering pile *e* until it strikes against the stop *p*. The sucker cups *i* then release the sheet. During the forward movement of the sheet the blow pipe *q* has executed an oscillating movement to the position shown in full lines, and, as soon as the sheet has been released by the grippers *c*, it blows upon the front end of the sheet which is consequently pressed on the pile. During the movement of the sheet in the reversed direction the blow pipe *q* oscillates backward into the position indicated in dotted lines and blows, as soon as the sheet has been released by the sucker

cups *i*, upon the rear end of the sheet. The air under pressure which acts upon the sheet is preferably heated so that the ink on the sheet is dried. Means for rocking the blow pipe *q* are shown in Figure 3 but it is to be understood that the said means form no part of the present invention and that any convenient mechanism may be employed for the purpose in question. The curved guide bar *o* is adjustably mounted on the frame *r*, as shown in Fig. 3, so that the sheet delivering device may be used for sheets of different lengths. The eccentric *m*, which controls the movement of the toothed segment *l*, is adapted to be adjusted on a scale in accordance with the height of the sheet.

In order to permit the printer to pull out single sheets to examine the printing the curved guide bar is arranged so that it can be removed. This arrangement is shown in Fig. 3. When the lever *s*, arranged on the frame *r*, is turned, the frame *r* and with it the curved guide bar *o* is pushed out in a lateral direction, so that the grippers *c* open in this case only when the roller lever strikes against the second curved bar *t*. The sheet then drops upon a support *u* so that it may be removed by hand. The lever *s* is connected with a device for shutting off the vacuum so that the sucker cups *i* do not suck on the sheet *a* when the curved guide bar *o* has been removed.

Instead of the grippers on carriage *h* being composed of the suction pipe *h*, any other element may be provided for gripping the rear edge of the sheet, as for instance, a mechanical gripper *v* mounted on the car-

riage *h*. This arrangement is shown in Fig. 2.

I claim:

1. In a sheet delivering device for printing presses, gripper elements conveying the sheets from the printing cylinder to a second group of gripper elements which moves in the direction of the conveying movement, 40 grips the sheet and reverses its direction of movement after the sheet has been released by the first mentioned conveying elements, a blowing device which executes an oscillating movement in a forward direction during 45 the forward movement of the sheet and a backward oscillation during the rearward movement of the sheet, the air blowing at first upon the front part and afterward upon the rear end of the sheet.

2. In a sheet delivering device for printing presses, gripper elements conveying the sheets from the printing cylinder to a second group of gripper elements which moves in the direction of the conveying movement, 50 grips the sheet and reverses its direction of movement after the sheet has been released by the first mentioned conveying elements, a blowing device which executes an oscillating movement in a forward direction during 55 the forward movement of the sheet and a backward oscillation during the rearward movement of the sheet, the air for the blower being preliminarily heated so that the blowing device serves at the same time as a 60 drying device.

In testimony whereof I affix my signature.

ALFRED FALLOT
